June 26. 1832

Edward Hale of Boston, Massachusetts,
Seller's Patent

The Schedule referred to in these Letters Patent and making part of the same containing a description in the words of the said Edward Hale himself of his improvement in the Standing Press called the Boston Press.

To all persons to whom these presents shall come, Be it known that I, Edward Hale of the City of Boston, County of Suffolk and Commonwealth of Massachusetts, mechanic, have invented, constructed made and applied to use, a new and useful improvement in the Standing Press, called the Boston Press, and that the following is a full and exact description of the construction and operation of the said machine as invented or improved by me. I make a strong timber frame of four pieces including seven feet in the clear. The upright pieces are six inches thick, the top and bottom pieces are four inches thick, and they are each and all ten feet wide. There are two other pieces which serve for plaster and toggle guides, about 4 inches by 3, framed into the top and bottom pieces standing upright 3 feet apart and parallel with the other uprights. These four uprights are perforated horizontally and in the same line for the purpose of receiving the pivots of the toggle screws. I make and use two toggle screws, they are 3 feet long, and one & a half inch in diameter. They have a slot well turned on each end & are fitted to the holes aforesaid, which are thro' the centre of each upright piece. On the end of each toggle screw which plays in the outside upright piece and close to the pivot is made fast a dowlated wheel 3 feet diameter, for the purpose of revolving the toggle screws. These wheels are driven by pinion wheels about seven inches diameter fixed upon a long arbor extending from one great wheel to the other, on the backside of the machine.

One pinion wheel is made to match and drive the great wheel directly, but the other is made to match and drive an intermediate pinion wheel which matches and drives the great wheel, by which means the direction of the great wheel is inverted. On the right hand side or end of the machine, the aforesaid long arbor extends thro' the top, so far as to admit two other wheels

X 7140

to be made fast to it, about three inches from each other, the outer one being about half the diameter of the other. Then by means of a bridge made fast in the outside of the upright post a crank arbor is fitted, parallel to the aforesaid long arbor, having elongated pivot, so that it may slide and wise about three inches for the purpose of shifting gearing. It has two wheels fixed upon it, one of which is equal in diameter to that of the largest wheel on the long arbor and the other is so large as to extend to, and drive the smaller wheel on the extended end of the long arbor, so that when these are in gear, the other wheels are out of gear, and so alternately. By which means, the motions of the machine, may be accelerated or retarded at option. On the last mentioned arbor is a crank by which the machine is moved. On each large screw, first mentioned a strong spherical nut having pivot, on opposite sides in a line with each other, about six inches long and one and a half inches in diameter. There are two toggle joints, one on each toggle bar, suspended in an upright position, on the pivot of the spherical nuts.

Each arm of the toggles is three feet long one foot wide and two inches, and a half inch thick either solid or open work somewhat like a section of a ladder having three slats or rounds, across. The outside slats being six inches from the ends of the side bars. The inner ends of the side bars are excavated, across like common plow toyes, and fitted to the pivot of the spherical nuts, and then held and supported by small hinges, skewed fast to the edges of the toggle bars. The outermost ends are a little enlarged somewhat like one side of a butt hinge joint, and bored thro large enough to receive a bolt two inches diameter. These bolts are fifteen inches long and project on each side of the toggle bar, enough to receive the heads of the platen rods. There are eight platen rods, they are six feet long and one inch and a half thick, all formed alike. The end of each rod is enlarged and perforated, so as to fit and screw on one end of the aforesaid bolts. The other ends have screw threads cut on them to the distance of six inches, and two strong nuts, fitted to each one. Two of these rods are suspended on the upper end of each toggle, hanging

downwards, and two swivelled on the lower end of each toggle. Standing upwards, the upper ends of the toggles are connected together by a second rod of the same size of the platen rods, perforated at each end and swivelled on the aforesaid bolts at the middle of them; and the lower ends of the toggles are connected by a similar rod and in the same manner, these rods being just so long as to keep the outermost ends of the toggles in contact with the platen and toggle guides. These rods pass thro' nut & slide up & down in mortises, made thro' the platen and toggle guides, for that purpose. There are two platens, three feet long and two feet wide and of such thickness as to render them sufficiently strong. They have a hole drilled thro' each corner of a proper size to receive the lower end of a platen rod, and they have a recess cut in each end of an exact size of the platen and toggle guides and fitted to them that they may slide up and down without any end shear or lateral play. One platen is a little wider than the other which is suspended on the four platen rods descending from the uppermost ends of the toggles. A nut is first screwed on the end of each rod, the platen is then placed face side uppermost, and each rod placed in its respective corner, and a nut screwed on underneath the platen. The other four rods are next armed with the shoulder nuts, the platen placed on them with the face side downwardly and nuts screwed on to confine it there. The platens are adjusted when their faces are parallel to each other and perpendicular to this line of motion. For a further support of the frame I insert a strong brace across each corner which is made tight by screwing a nut on each end on the outside of the frame. What I claim as my invention and improvement, in the above described machine is the construction and arrangement of those parts which connect the platens and toggles and the advantages which result from such arrangements.

In testimony that the above is a true specification and description of my said improvement, I have hereunto set my hand this 28 day of May in the year of our Lord one thousand eight hundred & thirty two.

Witness, { John Daigle }
{ Dennis O' Hallis }

James Hale
